(57) **CLAIM**

The ornamental design of a fluid operated wrench, as shown and described.

DESCRIPTION

FIG. 1 is a perspective view of a fluid operated wrench showing my new design;

FIG. 2 is a top plan view thereof;

FIG. 3 is a side view thereof; which is a mirror image of the opposite side thereof;

FIG. 4 is a rear view thereof;

FIG. 5 is a front view thereof; and,

FIG. 6 is a bottom view thereof.

The broken lines showing environmental in the drawings are for illustrative purposes only and form no part of the claimed design.
